UNITED STATES PATENT OFFICE.

THOMAS E. SMYTHE, OF GRAND RAPIDS, MICHIGAN.

PNEUMATIC PUMP.

Application filed July 30, 1921. Serial No. 488,593.

To all whom it may concern:

Be it known that I, THOMAS E. SMYTHE, a citizen of the United States, residing at Grand Rapids, in the county of Kent and 5 State of Michigan, have invented certain new and useful Improvements in Pneumatic Pumps, of which the following is a specification, reference being had to the accompanying drawings.

10 This invention relates to pumping mechanisms, and particularly to that class of pumps wherein air is used as a means for forcing water from a lower to a higher level.

15 This invention has the same object as the pneumatic pump patented to me on June 7, 1921, #1,380,603, but a more specific object of the invention is to simplify pumping mechanisms of this character by doing 20 away with a plurality of controlling floats and like parts.

25 A further object is to provide a construction of this character wherein a constant discharge of water is secured when a faucet is turned on and wherein a great saving in compressed air is secured, and in this connection to provide a single controlling float having therein air which is compressed by the rise of water in the float, this float 30 acting to control the compressed air valve and the air in the float also acting as the means whereby water from the upper container or receptacle is discharged.

35 Other objects have to do with the details of construction and arrangement of parts as will appear more fully hereinafter.

My invention is illustrated in the accompanying drawings, wherein:—

40 Figure 1 is a vertical sectional view of my pneumatic pump showing the parts in position where water is being discharged from the lower tank;

45 Figure 2 is a like view to Figure 1 but showing the position of the parts when the lower tank is filling and water is being discharged from the float.

50 Referring to the drawings, 10 designates a well, cistern, or like water collecting reservoir, and disposed within this well 10 is the lower tank 11 having the heads 12 and 13 and these heads are connected by tie rods 14, and the lower head is provided with an inlet opening 15 controlled by a check valve 16 which is held closed by pressure within the tank and is opened by pressure exterior 55 to the tank. The upper head 12 is formed

with a valve seat 17 of a check valve 18, the stem of this valve being cruciform in cross section and operating within a pipe 19 which extends downward from the head 12 almost to the check valve 16. 60

Disposed above the tank 11 is the upper tank 20, which may be disposed in any suitable location above the well and at any desired distance from the tank 11. This tank 20 is closed at its lower end but at its upper end is provided with the small centrally disposed opening 21. The head 22 forming the top of this tank is held in place by screws to the side wall of the tank. The water in this tank 20 is not discharged and 65 simply constitutes the water of flotation for a more or less buoyant combined float and tank 23. This tank 23 at its lower end has a guide spindle 24 which operates within a centrally disposed guide recess 25 in the bottom of the tank 20 and the upper end of the floating tank 23 is formed with an aperture 26. Passing loosely through the aperture 21 and passing into the floating tank 23 by means of the aperture 26 and connected to move with this floating tank 23 is a rod 27 which is tubular from its lower end to a point above the tank 20. Above this tubular duct 28 the rod 27 is solid and is provided with the two spaced stop 70 collars 29 and 30 held in place by set screws. The tubular portion of the rod 27 is formed with an angularly disposed outlet 31, to 75 which a flexible pipe section 32 is connected, the outer end of this flexible pipe section 32 communicating with a vertically disposed branch pipe 33 extending to and opening into the water discharge pipe 34. The inner end of this water discharge pipe is formed as a T to support the tank 20 at its 80 upper end and at its lower end to engage with the head 30 above the valve 18. The discharge end of the water discharge pipe 33 may be provided with a faucet 35. This 85 faucet is merely shown to illustrate the fact 90 that any suitable valve may be provided on the discharge pipe line 34 and at any suitable point along this line. In other words, the pipe line 34 may be the house system and have a plurality of faucets. 95

100 Mounted upon a bracket 36 extending upward from the head 22 and forked or bifurcated at its upper end is a bell-crank lever 37, the horizontal arm of which is provided with a bulbous head 38 bored to fit 110 loosely around the rod 27 and disposed be-

tween the stops 29 and 30. The depending arm of this bell crank lever is also apertured, as at 39, and at its lower end is notched for the reception of the upper end 5 of an S-shaped spring 40, the lower end of which is supported in a nick 41 formed in the bracket 25. Extending upward from the head 12 is an air line pipe 42 which discharges at its lower end into the tank 11 10 and which extends upward exteriorly of the tank 20 and is connected at its upper end to a valve casing 43. This valve casing is formed with an inlet port and valve seat 44 connecting with an air inlet pipe 45, in 15 turn connected to any source of compressed air.

Disposed within the valve casing is an air inlet valve 46 carried by a body 47, the rear end 48 of which constitutes an exhaust valve. 20 The rear end of this valve body is formed with a cruciform stem 49 extending outward through an exhaust aperture 50 in the rear end of the valve casing and this stem rearward of the cruciform portion extends loosely 25 through the aperture 39 in the depending arm of the bell crank lever and is provided with two adjustable stops 51 disposed on each side of the depending arm of lever 37. The valve 46 is urged to its seat by a spring 30 52 disposed around the valve body 47. When the valve 46 is seated, it closes the inlet opening 44 for the air and thus cuts off communication between the lower tank 11 and the air but opens communication between the 35 lower tank and the exhaust port 50. When the valve is retracted, however, it opens communication between the air inlet pipe 45 and the lower tank and closes communication between this lower tank and the exhaust port, 40. The operation of this mechanism is as follows: Assume that the mechanism is in the position illustrated in Figure 1 and the lower tank 11 is more or less filled with water and this water is being forced out through the 45 pipe 19 by means of the compressed air passing downward through the air line 42 into the upper end of the chamber or tank 11. The water is thus being forced out through the water line pipe 34 and a portion of this 50 water will be forced up the pipe 43 and into the duct 28 and so into the lower portion of the floating tank 23. This tank at this time is more or less filled with air so that it has risen to its highest position. As water flows 55 into the floating tank 23, however, the level of water will rise in the tank 23 and the air in the upper portion of the tank will be compressed. When the water rises to a predetermined height in the tank 23, it will increase 60 the weight of this tank sufficiently so that the tank will move downward, carrying with it the rod 27. At this time the water in tank 11 has been discharged. As the rod 27 moves downward under the weight of the 65 floating tank 23, the stop 29 will engage the

head 38 and cause the bell crank lever 37 to snap over into contact with one of the stops 51 and shift the valve formed of the parts 47 and 46 to a closed position, cutting off the supply of air to the lower tank and opening 70 exhaust from this lower tank. The floating tank 23 is now in its lowered position and the parts are as illustrated in Figure 2. In this position of the parts, the air in the lower tank is exhausting, water is flowing into the 75 lower tank, while in the upper tank the pressure of the air compressed in the upper portion of the tank 23 is forcing the water out of this tank upward through the duct 28 and through the pipe branches 32 and 33 into 80 the pipe 34 and so out past the faucet 35, provided this faucet is open. Obviously when the faucet 35 is closed the action of the apparatus is stopped.

At the time that the floating tank 23 falls, 85 it will snap the bell crank lever 37 over, as heretofore described, to the position shown in Figure 2. When a sufficient quantity of water has been discharged from the tank 23 by the force of the air compressed within 90 this tank, the weight of the floating tank 23 is sufficiently lessened so that its buoyancy causes the floating tank to rise, lifting the rod 27 and causing the reversal of the valve 46, closing the exhaust port from tank 11 95 and establishing communication between the source of air and the tank 11 and the parts are again in the position shown in Figure 1. It will be noted that the S-shaped spring 40 acts to snap the bell crank lever 37 quickly 100 from one position to the other. In other words, this spring 40 resists movement of the bell crank lever until the axial line of the depending arm of the bell crank lever is central with respect to the notch 41 and then 105 this spring 40 acts to urge the depending arm 39 over against the innermost stop 51. This movement of the bell crank lever of the spring is assisted by the spring 52 and by the weight of the float 23 and it is necessary 110 to use the spring 52 because of the fact that the valve 46 has to close against the pressure of air entering the port 44. On the reverse movement, however, the pressure of air entering through the port 44 assists in shifting 115 the valve body 47 to the position shown in Figure 1 against the action of spring 52.

While I have illustrated an embodiment of my invention which is thoroughly positive in its action and effective, I do not wish to 120 be limited thereto, as it is obvious that the principle of the invention might be embodied in other forms. I have illustrated the construction diagrammatically to a certain extent for the reason that the principle 125 might be embodied in many different forms.

I claim:—

1. In pneumatically operated mechanism, a fixed liquid filled tank, a hollow air-tight float therein, a fixed liquid receiving tank, 130

- and means operated by the full rise of the float causing the discharge of a portion of the liquid in the receiving tank into the float to thereby compress the air in the upper 5 portion of the float and cause the float to sink, and means operated upon the full downward movement of the float causing the filling of the receiving tank and permitting the discharge of water from the 10 float by the air compressed therein.
2. In a pneumatically operated mechanism, a liquid filled tank, a hollow air-tight float therein, a controlling valve operated by the rise and fall of the float, a single 15 liquid inlet and discharge pipe entering the float, and means operating automatically to alternately cause the discharge of liquid through said pipe into the interior of said float to thereby compress the air therein and 20 increase the weight of the float and permit said compressed air to force the water out of the float through said pipe to thereby decrease the weight of the float to thus cause the alternate rise and fall of the float.
- 25 3. A pneumatic pump including a lower chamber having an inlet port and a discharge pipe, check valves controlling passage through the port and pipe, an upper liquid containing tank, a hollow, air-tight 30 float therein, a pipe leading from the discharge pipe and discharging into the lower portion of the float in all positions of the float, and means controlled by said float for establishing communication between the upper portion of said lower chamber and a source of compressed air or 35 between the upper portion of said lower chamber and the exhaust port.
4. A pneumatic pump including a lower 40 chamber having an inlet port and a discharge pipe, check valves controlling passage through the port and pipe, an upper liquid containing chamber, a hollow, air-tight float therein, a pipe leading from the discharge pipe and extending through said upper chamber into the float and discharging into the lower end thereof, an air supply pipe extending into the upper end of the lower chamber, a valve casing having an air 45 inlet port and an air exhaust port communicating with the air pipe, and means controlled by the rise and fall of the float for shifting said valve to alternately establish communication between the inlet of the 50 valve casing and the air pipe and between said air pipe and the exhaust port.
5. A pneumatic pump comprising a lower 55 chamber having an inlet port and a discharge pipe, check valves controlling passage therethrough, an upper liquid containing tank, a hollow, air-tight float disposed therein, a tubular rod to which the float is attached and extending out through the upper end of the tank, the rod discharging at the lower end of the float, a tubular connection leading from the discharge pipe to the interior of said hollow rod exteriorly of the upper tank, a valve casing having an inlet port communicating with a source of compressed air, an exhaust port, a port communicating with the upper end of the lower tank, a valve therein in one position permitting the entrance of compressed air to 60 the valve casing and in another position closing the inlet port of the valve casing but opening the exhaust port, and means controlled by the rise and fall of the float for shifting said valve.
6. A pneumatic pump comprising a lower 65 chamber having an inlet port and a discharge pipe, check valves controlling passage therethrough, an upper liquid containing tank, a hollow, air-tight float disposed therein, a tubular rod to which the float is attached and extending out through the upper end of the tank, the rod discharging at the lower end of the float, a tubular connection leading from the discharge pipe to the interior of said hollow rod exteriorly of the upper tank, a valve casing having an inlet port communicating with a source of compressed air, an exhaust port, a port communicating with the upper end of the lower tank, a valve therein in one position permitting the entrance of compressed air to 70 the valve casing and in another position closing the inlet port of the valve casing but opening the exhaust port, and means controlled by the rise and fall of the float for shifting said valve.
7. A pneumatic pump comprising a lower 75 chamber having an inlet port and a discharge pipe, check valves controlling passage therethrough, an upper liquid containing tank, a hollow, air-tight float disposed therein, a tubular rod to which the float is attached and extending out through the upper end of the tank, the rod discharging at the lower end of the float, a tubular connection leading from the discharge pipe to the interior of said hollow rod exteriorly of the upper tank, a valve casing having an inlet port communicating with a source of compressed air, an exhaust port, a port communicating with the upper end of the lower tank, a valve therein in one position permitting the entrance of compressed air to 80 the valve casing and in another position closing the inlet port of the valve casing but opening the exhaust port, and a valve shifting member operatively connected to the valve and to the rod acting to open the valve 85 casing to the inlet of compressed air upon the rise of the float and to open the exhaust port and close the inlet upon the fall of the float.
8. A pneumatic pump comprising a lower 90 chamber having an inlet port and a discharge pipe, check valves controlling passage therethrough, an upper liquid containing tank, a hollow, air-tight float disposed therein, a tubular rod to which the float is attached and extending out through the upper end of the tank, the rod discharging at the lower end of the float, a tubular connection leading from the discharge pipe to the interior of said hollow rod exteriorly of the upper tank, a valve casing having an inlet port communicating with a source of compressed air, an exhaust port, a port communicating with the upper end of the lower tank, a valve therein in one position permitting the entrance of compressed air to 95 the valve casing and in another position closing the inlet port of the valve casing but opening the exhaust port, and a valve shifting member operatively connected to the valve and to the rod acting to open the valve 100 casing to the inlet of compressed air upon the rise of the float and to open the exhaust port and close the inlet upon the fall of the float.
9. A pneumatic pump comprising a lower 105 chamber having an inlet port and a discharge pipe, check valves controlling passage therethrough, an upper liquid containing tank, a hollow, air-tight float disposed therein, a tubular rod to which the float is attached and extending out through the upper end of the tank, the rod discharging at the lower end of the float, a tubular connection leading from the discharge pipe to the interior of said hollow rod exteriorly of the upper tank, a valve casing having an inlet port communicating with a source of compressed air, an exhaust port, a port communicating with the upper end of the lower tank, a valve therein in one position permitting the entrance of compressed air to 110 the valve casing and in another position closing the inlet port of the valve casing but opening the exhaust port, and a valve shifting member operatively connected to the valve and to the rod acting to open the valve 115 casing to the inlet of compressed air upon the rise of the float and to open the exhaust port and close the inlet upon the fall of the float.
10. A pneumatic pump comprising a lower 120 chamber having an inlet port and a discharge pipe, check valves controlling passage therethrough, an upper liquid containing tank, a hollow, air-tight float disposed therein, a tubular rod to which the float is attached and extending out through the upper end of the tank, the rod discharging at the lower end of the float, a tubular connection leading from the discharge pipe to the interior of said hollow rod exteriorly of the upper tank, a valve casing having an inlet port communicating with a source of compressed air, an exhaust port, a port communicating with the upper end of the lower tank, a valve therein in one position permitting the entrance of compressed air to 125 the valve casing and in another position closing the inlet port of the valve casing but opening the exhaust port, and a valve shifting member operatively connected to the valve and to the rod acting to open the valve casing to the inlet of compressed air upon the rise of the float and to open the exhaust port and close the inlet upon the fall of the float and spring actuated.

ated means for yieldingly holding the valve in either of its positions.

8. A pneumatic pump comprising a lower chamber having an inlet port and a discharge pipe, check valves controlling passage therethrough, an upper liquid containing tank, a hollow, air-tight float disposed therein, a tubular rod to which the float is attached and extending out through the upper end of the tank, the rod discharging at the lower end of the float, a tubular connection leading from the discharge pipe to the interior of said hollow rod exteriorly of the upper tank, a valve casing having an inlet port communicating with a source of compressed air, an exhaust port, a port communicating with the upper end of the lower tank, a valve therein in one position permitting the entrance of compressed air to the valve casing and in another position closing the inlet port of the valve casing but opening the exhaust port, a bell crank lever operatively connected to the valve and with which the float rod has sliding engagement, and stops on the float rod adapted to engage said bell crank lever to shift it as the rod nears its fully raised position or its fully lowered position.

9. A pneumatic pump comprising a lower chamber having an inlet port and a discharge pipe, check valves controlling the passage of liquid therethrough, an upper liquid containing tank, a hollow, air-tight float disposed therein, a tubular rod to which the float is attached and extending out through the upper end of the tank, the rod discharging at the lower end of the float, a tubular connection leading from the discharge pipe to the interior of said hollow rod exteriorly of the upper tank, a valve casing having an inlet port communicating with a source of compressed air, an exhaust port, a port communicating with the upper end of the lower tank, a valve therein in one position permitting the entrance of compressed air to the valve casing and in another position closing the inlet port of the valve casing but opening the exhaust port, a bell crank lever operatively connected to the valve and with which the float rod has sliding engagement, stops on the float rod adapted to engage said bell crank lever to shift it as the rod nears its fully raised position or its fully lowered position, and resilient means yieldingly resisting the initial movement of the bell crank lever but assisting the final movement of the bell crank lever to either of its operative positions.

10. A pneumatic pump comprising a lower chamber having an inlet port and a discharge pipe, check valves controlling passage therethrough, an upper liquid containing tank, a hollow, air-tight float disposed therein, a tubular rod to which the float is attached and extending out through the up-

per end of the tank, the rod discharging at the lower end of the float, a tubular connection leading from the discharge pipe to the interior of said hollow rod exteriorly of the upper tank, a valve casing having an inlet port communicating with a source of compressed air, an exhaust port, a port communicating with the upper end of the lower tank, a valve therein in one position permitting the entrance of compressed air to the valve casing and in another position closing the inlet port of the valve casing but opening the exhaust port, a bell crank lever operatively connected to the valve and with which the float rod has sliding engagement, stops on the float rod adapted to engage said bell crank lever to shift it as the rod nears its fully raised position or its fully lowered position, a spring urging the valve to a position to close the air inlet, and a spring yieldingly resisting the initial movement of the bell crank lever from either of its positions but assisting movement of the bell crank lever from one position to the other after it has passed a median line intersecting its center of motion.

11. A pneumatic pump comprising a lower chamber having an inlet port at its lower end and an outlet pipe extending from its upper end, check valves in said port and pipe, an upper liquid filled chamber, a hollow, air-tight float disposed therein for vertical movement, a rod attached to said float and extending out through the upper end of the chamber, said rod being hollow to provide a duct opening at its lower end adjacent the bottom of the float and at its upper end above said chamber, a flexible connection extending from said duct, a pipe leading from the flexible connection to the discharge pipe of the lower chamber, a valve casing having a compressed air inlet port, an exhaust port, an outlet port leading from the valve casing to the upper end of the lower chamber, a valve in the casing in one position closing the exhaust port and opening the inlet port and in the other position closing the inlet port and opening the exhaust port, and means for shifting said valve comprising spaced stops mounted on the rod, a lever having its end disposed between said stops and through which the rod slides, a stem on the valve having spaced stops, the other end of said lever having sliding engagement with said stem and between said stops, and resilient means yieldingly resisting an initial movement of said lever to either of its positions but assisting the final movement of the lever.

12. A pneumatic pump comprising a lower chamber having an inlet port at its lower end and an outlet pipe extending from its upper end, check valves in said port and pipe, an upper liquid filled chamber, a hollow, air-tight float disposed therein for

vertical movement, a rod attached to said float and extending out through the upper end of the chamber, said rod being hollow to provide a duct opening at its lower end adjacent the bottom of the float and at its upper end above said chamber, a flexible connection extending from said duct, a pipe leading from the flexible connection to the discharge pipe of the lower chamber, a valve casing having a compressed air inlet port, an exhaust port, an outlet port leading from the valve casing to the upper end of the lower chamber, a valve in the casing in one position closing the exhaust port and opening the inlet port and in the other position closing the inlet port and opening the exhaust port, means for shifting said valve comprising spaced stops mounted on the rod, a bell crank lever having one end disposed between said stops, this end of the lever having sliding engagement with the rod, a stem on the valve, spaced stops on the stem, the other end of the lever having sliding engagement with said stem between said stops, and an S-shaped spring supported at its lower end and having its upper end engaging one arm of the bell crank lever, said spring resisting an initial movement of the bell crank lever from either of its positions but assisting final movement thereof.

13. A pneumatic pump comprising a lower chamber having an inlet port and a discharge pipe, check valves therein, an upper

liquid filled tank, a float therein, means for establishing communication between the source of compressed air and the upper portion of the lower tank or between the upper portion of said lower tank and an exhaust port, including a valve operatively connected to and shifted in one direction by the rise of said float and in the other direction by the fall thereof, and means acting automatically for alternately increasing or decreasing the weight of the float to cause it to alternately descend or ascend.

14. In a pneumatic pump, a lower chamber having an inlet port, a discharge pipe, check valves therein, an upper liquid containing tank, a hollow, air-tight float therein, means for discharging compressed air into the upper portion of the lower chamber or exhausting compressed air therefrom including a valve, means operatively connecting the valve to the float to shift the valve by the rise and fall of the float, and means for causing a discharge of a portion of the liquid discharged from the lower chamber into said float to thereby increase the weight of the float to cause its descent, the compressed air trapped in the upper portion of the float then acting to discharge the liquid from the float to thereby cause the rise of the float.

In testimony whereof I hereunto affix my signature.

THOMAS E. SMYTHE.
